PENDANT CROSS OR THE LIKE

Arthur Albanese, Cranston, R.I., assignor to Marvel Jewelry Mfg. Company, Providence, R.I., a corporation of Rhode Island

Filed Oct. 4, 1965, Ser. No. 87,308

Term of patent 14 years

(Cl. D45—16)

FIG. 1.

FIG. 2.

FIG. 4.

FIG. 3.

I claim:

The ornamental design for a pendant cross or the like, as shown.
